DESIGN FOR A SHIP MODEL ORNAMENT

Herbert A. Siemund, Chicago, Ill., assignor to
Franklin Die Casting Company, Chicago, Ill.,
a corporation of Illinois

Application August 9, 1935, Serial No. 58,047

Term of patent 14 years

To all whom it may concern:

Be it known that I, Herbert A. Siemund, a citizen of the United States of America, residing at 3948 Waveland Avenue, Chicago, Illinois, have invented a new, original, and ornamental Design for a Ship Model Ornament, of which the following is a specification, reference being had to the accompanying drawing, forming a part thereof.

Fig. 1 is a perspective view of my ship model ornament and

Fig. 2 is a view in detail of my unitary split front sail.

The characteristic feature of my design resides in the unitary split front sail. Said sail consists of two substantially triangular shaped portions separated by a split running from adjacent the top to the bottom of the sail where the two portions are connected by a strap which is an integral part of said front sail.

I claim:

The ornamental design for a ship model ornament substantially as shown and described.

HERBERT A. SIEMUND.
